UNITED STATES PATENT OFFICE.

BRYSON D. HORTON, OF DETROIT, MICHIGAN.

CONNECTING DEVICE FOR ELECTRICAL SWITCHES.

1,320,619.

Specification of Letters Patent.

Patented Nov. 4, 1919.

Application filed December 29, 1914. Serial No. 879,482.

To all whom it may concern:
Be it known that I, BRYSON D. HORTON, a citizen of the United States, residing in Detroit, in the county of Wayne and State 5 of Michigan, have invented certain new and useful Improvements in Connecting Devices for Electrical Switches, of which the following, taken in connection with the accompanying sheet of drawings, is a full, clear, 10 and concise description thereof and such as will enable one skilled in the art to make and use the same.

My invention relates more particularly to improved means for connecting movable switch contacts of the knife-blade variety 15 to a bar or other actuator member. The object of my invention is to provide such means of cheap and inexpensive construction. Broadly speaking, my invention comprises a device for suspending the blade contact beneath the bar or actuator member by a single instrumentality which straddles or partly surrounds the same, this member, preferably, being formed of a 20 single piece of metal, or wire, slotted and bent to proper form so as to accommodate both the blade and the actuator member.

In the figure of the accompanying drawing, I have shown one of the many embodiments of which my invention is susceptible. 30 As shown, a bar or actuator member 1 of suitable material is associated with a knife blade 2. The bar or actuator member is preferably, though not necessarily, cylindrical in form, and usually made of insulating material, or of metal with an insulating sleeve, such material, however, forming no part of my invention in the present case. The knife blade contact 2 is usually rectangular in cross section. The knife blade may 40 be mounted at one end, as 2^a, for oscillatory movement for making and breaking electrical contact at the other end with a second fixed contact not shown. The bar 1 and blade 2 are arranged at substantially right angles to one another. At the point of connection between the actuator member and the blade contact 1 preferably cut away, as at 3, a portion of the blade, 45 thus leaving an aperture having the contour of the actuator member so that the latter may find a seat therein, in order that lateral movement of the blade with respect to the actuator member is prevented.

Such a mounting as has thus been generally described, has the advantage that the actuator member and blade are caused to maintain a positive operative relationship, while, at the same time, the possibility of undesirable relative movement between them 55 is eliminated.

The connector member specifically is provided with a saddle, or encircling portion, 5, partially or wholly surrounding the actuator member when in blade supporting 60 position, the blade supporting portion of the connector being directed downwardly beneath the bar, as shown. The depending portion of the connector is provided with an aperture or space 6, laterally directed with 65 respect to the rock arm to accommodate the knife-blade contact.

As thus described it will be understood that the bar and pivoted knife-blade contact, when coöperatively associated through 70 the instrumentality of the connecting device described, is such that the operation of the actuator member will cause the switch arm to move on its pivot toward or away from the stationary contact, in a positive manner, 75 and without relative movement between the two.

In the figure the connector is illustrated as being formed of a single piece of sheet metal bent into U form with apertured free 80 ends, the actuator bar being positioned through the apertures of the ends and the knife-blade resting in, or projecting through, the U, a binding screw 7 being employed 85 to engage the knife-blade so that the latter 90 may be forced upwardly into close contact with the actuator bar.

In the form described, the parts are caused to have a very intimate and close connection without the use of binding screws 95 and the like; the connecting member or device may be made of a single sheet of spring metal bent to a hook shape, with one of its ends slotted as at 6, to accommodate the switch blade 2, the other end having 100 an open slot to also accommodate the switch blade 2, the bar resting within the cutaway portion 3 of the blade. The connecting member therefore straddles the bar. The bar 2 may be provided at its lower edge 105 with a notch 4 to receive the connecting member and thereby block the bar in position.

The encircling portion 5 is adapted to cause the binding of the actuator member against the knife blade and in the cut-out portion 3, and in conjunction with the notch 4, to positively hold the parts together in a close anti-rattling association.

While I have shown but one embodiment of my invention, it is obvious that many other forms could be devised, and structural changes made without departing from the spirit or scope of my invention as defined by the following claims, and I therefore desire it to be understood that the drawings and description are to be considered as illustrative and not in the limiting sense.

Having thus described my invention, what I claim is:

1. In the combination of a bar, a rectangular knife blade arranged at substantially right angles thereto and having a cut out portion to receive said bar, and a connector comprising a single piece of sheet material curved to clamp around said bar, and having one end extended and provided with a closed slot therein to receive said rectangular knife blade, the other end of said connector having an open slot adapted to receive a portion of said knife blade, said connector adapted to cause the binding of said rectangular member in said first mentioned slot, and against said bar.

2. The combination of a bar, a rectangular knife blade arranged at substantially

right angles thereto and having a cut out portion to receive said bar, and a connector comprising a single piece of material curved to clamp around said bar, and having one end extended and provided with a closed slot therein to receive said rectangular knife blade, the other end of said connector having a slot adapted to receive a portion of said knife blade, said connector adapted to cause the binding of said rectangular member in said first mentioned slot, and against said bar.

3. A connector adapted to connect a bar and a rectangular member arranged at right angles thereto, comprising a single piece of sheet material curved to clamp around said bar, and having one end extended and provided with a closed slot therein to receive said rectangular member, the other slot of said connector having an open end adapted to receive a portion of said rectangular member, said connector adapted to cause the binding of said rectangular member in said first mentioned slot and against said bar.

In witness whereof I have hereunto set my hand in the presence of two subscribing witnesses.

BRYSON D. HORTON.
